FIG. 1

FIG. 2

FIG. 3

FIG. 4

FIG. 5

FIG. 6

FIG. 7

FIG. 8

UNITED STATES PATENT AND TRADEMARK OFFICE
CERTIFICATE OF CORRECTION

PATENT NO. : Des. 499,710 S
DATED : December 14, 2004
INVENTOR(S) : Tej Chauhan

Page 1 of 1

It is certified that error appears in the above-identified patent and that said Letters Patent is hereby corrected as shown below:

Title page.

Item [57], **ABSTRACT**,

Fig.7, "Fig. 7 is a perspective view thereof" has been replaced with -- Fig. 7 is a perspective front view thereof --

Fig. 8, "Fig. 8 is a perspective view thereof" has been replaced with -- Fig. 8 is a perspective rear view thereof --

Signed and Sealed this

Twenty-ninth Day of March, 2005

JON W. DUDAS
Director of the United States Patent and Trademark Office
